UNITED STATES PATENT OFFICE.

AMBROSE E. DEIBERT, OF KANSAS CITY, MISSOURI, ASSIGNOR OF ONE-HALF TO EDWARD J. LAWLESS, OF SAME PLACE.

CAR-BRAKE.

SPECIFICATION forming part of Letters Patent No. 392,316, dated November 6, 1888.

Application filed April 7, 1888. Serial No. 269,920. (No model.)

To all whom it may concern:

Be it known that I, AMBROSE E. DEIBERT, of Kansas City, Jackson county, Missouri, have invented certain new and useful Improvements in Car-Brakes, of which the following is a full, clear, and exact description, reference being had to the accompanying drawings, forming a part hereof.

My invention relates to brakes that are applied by the momentum of the car or cars; and it may be said to consist in the peculiar construction, combination, and arrangement of devices hereinafter set forth, and pointed out in the claims.

In the drawings, which illustrate the manner of carrying out my invention, Figure 1 is a perspective view of the brake applied to a car-truck. Fig. 2 is a longitudinal section through power mechanism that is located on the axle. Fig. 3 is a detail view of a stationary cam used in making up the invention, and Fig. 4 is a similar view of a rocking cam.

The letter A indicates the car-axle, upon which is keyed or otherwise firmly secured, so as to rotate therewith, a hollow dish-shaped friction-cylinder, B, said cylinder having a long sleeve, B', upon which the main portions of the power mechanism are mounted. Said cylinder is provided with an outwardly-flaring bore, 10, which is engaged by a correspondingly-tapered or inclined friction-plug, C. Cast integral with or otherwise firmly secured to one side of said plug is the winding-spool D, upon which the chain p is to be wound and unwound during operation of the brake, as shown.

The end of the spool D that is opposite plug C is provided with an annular groove, i, which is engaged by a corresponding flange, j, formed upon stationary cam E, so that said cam and said spool will be loosely connected during operation, and so that said spool will be permitted to revolve upon sleeve B'.

Stationary cam E is provided with an annular series of inclines, c, upon the side that is farthest from the spool D, and which are engaged by corresponding inclines, d, formed upon the inner side or surface of rocking cam F, the said stationary cam being provided with a perforated ear or lug, a, by means of which it is fixed to the car-frame I, (a screw-buckle, b, being used for this purpose,) while the said rocking cam is also provided with a

perforated ear, a', to which the operating-rod b' is connected. Said rocking cam is also provided with a flange, g, which loosely engages an annular groove, g', found in exterior sleeve, G, and which latter is secured in position upon sleeve B' by means of a threaded nut, H, and set-screw 13. The free end of sleeve B' is provided with a screw-thread upon its exterior, which is engaged by corresponding threads on sleeve G and nut H, as shown.

The stationary cam E and rocking cam F are provided with circular centrally-located apertures 2 and 3, respectively, which are a little larger in diameter than sleeve B', so that said cams may be loosely mounted upon the sleeve. The winding-chain p has one end secured to spool D by means of a transverse pin, k, or in any other preferred manner. In the construction shown, however, the pin k is secured in position by means of another pin or key, q, being passed through one of its ends and through the spool-casting.

The plug C is cored out, so that it will be hollow and shell-like for the purpose of providing it with internal chambers or recesses L, in which latter lubricating materials are to be located, and branch passages—such as 6, 7, and 8—lead from said lubricating-chambers to the several frictional surfaces of the mechanism.

I prefer to fill the chamber or chambers L with cotton waste L', so that the lubricant will be steadily and permanently fed to the wearing surfaces.

With this construction it will be seen that the frictional parts of the apparatus are comparatively well protected from dust and dirt, and, therefore little wear will take place by reason of the action of grit and dirt.

The operation of the brake is as follows: The operating-rod b' is connected with a suitable hand-lever, J, and upon said lever being adjusted to the position indicated in Fig. 1 the cam F will be rocked or revolved slightly, (in the direction indicated by the arrows,) and the inclined surfaces d, with which it is provided, will forcibly engage the surfaces c upon cam E, and said cam E will be forcibly pushed to one side in a longitudinal direction upon axle A, as will also spool D and plug C, and the inclined or tapered periphery 12 of said plug will be forced within and into intimate con-

tact with the flaring bore 10 of cylinder B, and said plug, carrying the winding-spool, will be revolved with the axle A, winding the chain p upon the spool and applying the brakes to the wheels of the car; it being evident, of course, that chain p can be connected to the brake-beams in any desired way. Throwing lever J in a direction opposite that just described will cause a reverse action to take place, and the plug C and spool D will be drawn away from the friction-cylinder B, permitting said spool to revolve backward upon sleeve P', and the chain to unwind from the spool. The under portion of cam E is provided with a transversely-projecting flange, h, which is provided with inclined slots e, and which latter are engaged by corresponding pins, f, which project from the periphery of cam F. When the brakes are to be thrown off by reverse movement of the lever J, the pins will come in contact with the sides of slots e that are opposite or farthest from inclined surfaces e, and the said cam E and spool D and plug C will thereby be pulled away from the friction-cylinder, as before indicated.

Within the upper portion of cams E and F lubricating-recesses 15 are formed, which may contain waste or other lubricant-holding material, for the purpose of oiling the parts at their locality.

Heretofore much trouble has been experienced in brakes of this class in stopping upon steep grades or inclines, particularly where the brakes have been located upon cable-cars, the trouble having been that the car would run back and loosen the clutch or friction devices and thereby throw off the brakes, only a slight backward movement having been necessary to accomplish this. The reason of this has been want of power in the clutch and friction devices. With my construction and by the use of my invention such trouble is completely obviated, and the car or cars may be stopped upon comparatively steep inclines and will be held wheresoever necessary without backward movement. This is brought about, as will be understood, by means of the relative arrangement of the friction-cylinder B and plug C, said plug being in the form of a powerful wedge, and which when once forced into contact with the bore of the said cylinder holds the parts firmly to each other and thereby holds the brakes in a set position.

With brakes of this class heretofore in use, such as shown in Patent No. 263,529, the frictional devices were insufficiently powerful to hold a car or cars upon a steep incline.

It is evident that in carrying out the operation of my device numerous slight changes in the details—such as would suggest themselves to a skilled mechanic or a person of ordinary intelligence—could be resorted to without departing from the scope and spirit of my invention.

Having thus described my invention, what I claim is—

1. The combination, with a rotative supporting-axle, of a frictional cylinder having a flaring bore, a transversely-sliding friction-plug which engages the bore of said cylinder, and a non-rotative and a rocking cam for making contact between the plug and cylinder, substantially as and for the purpose specified.

2. In a car-brake, a friction-cylinder having a flaring bore, in combination with a transversely-sliding friction-plug, a winding-spool connected to said plug, and a non-rotative and a rocking cam for making contact between the said plug and said cylinder, substantially as and for the purpose specified.

3. In a car-brake, a friction-cylinder, a friction-plug, a winding-spool and a transversely-movable but non-rotative cam, and connections for making contact between said plug and said cylinder, substantially as and for the purpose specified.

4. In a car-brake, a friction-cylinder, a transversely-sliding friction-plug, a winding-spool, a transversely-movable but non-rotative cam, and a rocking cam, all mounted upon a common axle, substantially as described.

5. The herein-described car-brake arranged with a transversely-sliding but non-rotative cam, a rocking cam, and friction devices, substantially as described.

6. In the herein-described car-brake, a non-rotatable cam and a rocking cam, in combination with a winding-spool and friction devices, substantially as described.

In testimony whereof I affix my signature in presence of two witnesses.

AMBROSE E. DELBERT.
